UNITED STATES PATENT OFFICE.

WILLIAM B. CLEVELAND, OF CLEVELAND, OHIO.

DESIGN FOR A RAIL-BOND.

SPECIFICATION forming part of Design No. 31,373, dated August 8, 1899.

Application filed May 31, 1899. Serial No. 718,918. Term of patent 14 years.

To all whom it may concern:

Be it known that I, WILLIAM B. CLEVELAND, a citizen of the United States, and a resident of Cleveland, county of Cuyahoga, and State of Ohio, have invented and produced a new and original Design for Rail-Bonds, of which the following is a specification, reference being had to the accompanying drawings, forming a part thereof.

10 In said annexed drawings, Figure I represents a top plan view of my design. Fig. II represents a bottom plan view thereof, and Fig. III represents a side elevation.

The leading feature of said design consists 15 of a link formed of flat metal strips laid side by side and having each side portion of said link bent inwardly in the plane of the link and near its junction with one of the loop portions of the link, such bend occurring but 20 once in each such side portion and near each

such loop portion, said link having a cylindrical lug projecting from each loop. Said cylindrical lugs project from the same side of the link, as shown in Fig. III, and are enlarged at that portion immediately contiguous to said loops to form a plate-like structure, in which the loop portions of the link are embedded. On the side opposite that from which the lugs project said plate-like structure is given a quadrilateral contour, as 30 shown in Fig. I.

What I claim is—

The design for a rail-bond, substantially as shown and described.

Signed by me this 29th day of May, 1899. 35

WILLIAM B. CLEVELAND.

Attest:

D. T. DAVIES,
A. E. MERKEL.
